UNITED STATES PATENT OFFICE.

FREDERICK MANKEY, OF WILLIAMSPORT, PENNSYLVANIA.

DESIGN FOR A PANEL.

SPECIFICATION forming part of Design No. 16,237, dated September 8, 1885.

Application filed July 18, 1885. Term of patent 7 years.

To all whom it may concern:

Be it known that I, FREDERICK MANKEY, of Williamsport, Lycoming county, Pennsylvania, have invented and produced a new and original Design for Surface Ornamentation of Walls, &c., the same consisting of a panel, of which the following is a specification, reference being had to the accompanying photographs, forming part hereof.

10 Figure 1 is a plan view of a panel on which is formed my new design. Fig. 2 is a longitudinal section of the same. Fig. 3 shows four panels, similar to Fig. 1, in juxtaposition.

Similar letters of reference indicate like parts.

15 My design includes both the configuration or pattern hereinafter described, and also on the surface of the raised portions of said pattern an appearance of the grain different 20 from that which is seen on the flat or non-elevated parts of the panel. The exact appearance of the grain on said elevated portion cannot of course be limited to any specific arrangement of markings, inasmuch as the appearance of the grain will constantly vary. 25 In Fig. 1 the grain naturally runs longitudinally in the panel shown.

20 My design consists of a series of rhomboidal elevations, A, separated by channels B, and 30 disposed successively longitudinally the panel. Each elevation A has its sides or edges rounded, as shown. Along the base of the rhomboids A is a straight longitudinal channel, C, which separates said rhomboids A from another series of rhomboidal elevations, D, which elevations D are also rounded at their 35 edges and are separated by channels B, prolonged. Along the bases of the rhomboids D is

another longitudinal channel, similar to C, and at the opposite side of said channel another 40 row of rhomboids. As many rows of rhomboids may thus be employed as desired. The rhomboids A and D may be all of the same size; or the rhomboids D may be longer than the rhomboids A, as here shown, to add variety to the design.

45 A longitudinal section of a panel figured as above described is shown in Fig. 2, and exhibits a series of semicircular elevations, A, separated by flat portions B. In Fig. 3 I 50 show four panels having their surfaces ornamented as described and joined together, exhibiting a row of chevrons, E, having their points turned in one direction, and a row of chevrons, F, with their points turned in the 55 other direction, these chevrons being all of the same size. There is also a row of triangular figures—such as G H I—of varying sizes.

I claim—

1. The design for a surface ornamentation of 60 walls, &c., here shown and described, the same consisting in two or more series of raised rhomboids, A and D, the said rhomboids being separated by channels B and C.

2. The design for a surface ornamentation of 65 walls, &c., herein shown and described, the same consisting in two or more series of raised rhomboids, A and D, the said rhomboids being separated by depressions or channels B and C, and the surfaces of said rhomboids exhibiting a different appearance of grain from the flat or bottom portions of said channels.

70 FREDERICK MANKEY.
